[57] **CLAIM**

The ornamental design for a floss bobbin sheet, as shown and described.

DESCRIPTION

FIG. 1 is a top plan view for a floss bobbin sheet showing my new design, the bottom side of the article being identical in appearance to the top side illustrated in FIG. 1;

FIG. 2 is a side elevational view thereof, the opposite side being an identical image thereof;

FIG. 3 is a bottom elevational view thereof, the opposite side being an identical image thereof; and,

FIG. 4 is a top perspective view of a single floss bobbin thereof.

FIG. 2

FIG. 1

FIG. 3

FIG. 4
